UNITED STATES PATENT OFFICE.

LEONARD A. SEISS, OF TOLEDO, OHIO.

RHEOSTAT.

Application filed May 6, 1922. Serial No. 559,048.

To all whom it may concern:

Be it known that I, LEONARD A. SEISS, a citizen of the United States, and a resident of Toledo, in the county of Lucas and State of Ohio, have made an invention appertaining to a Rheostat; and I do hereby declare the following to be a full, clear, and exact description of the invention, such as will enable others skilled in the art to which it app pertains to make and use the same, reference being had to the accompanying drawings, and to the characters of reference marked thereon, which form a part of this specification.

15 My invention has for its object to provide a rheostat that may be readily assembled. It particularly has for its object to provide a supporting means for the parts of the rheostat that may be efficiently made and yet 20 when assembled with the rheostat parts will produce an exceedingly efficient rheostat.

The invention may be contained in structures that differ in their details. To illustrate a practical application of the invention 25 I have selected one of such structures as an example of structures containing the invention and shall describe it hereinafter. The structure selected is illustrated in the accompanying drawings.

30 Figure 1 of the drawings is a top view of the rheostat. Fig. 2 is a bottom view of the rheostat. Fig. 3 is a side view of the rheostat. Fig. 4 is a sectional view taken on the line 4—4 indicated in Fig. 2. Fig. 5 is an enlarged sectional view taken on the line 5—5 indicated in Fig. 2. Fig. 6 illustrates the top view of a stamping from insulating sheet material forming a part of the base or supporting member of the rheostat.

40 1 is a rotatable handle having an indicating pointer 2 that may be moved over a suitable dial formed on the top of the rheostat to indicate the amount of resistance introduced in a circuit by manipulation of the rheostat in the manner well known in the art. The handle 1 and the pointer 2 are connected to a shaft or rod 3 to which is also connected a spring contact 4. Rotation of the handle 1 causes rotation of the rod 3, the 45 pointer 2 and the spring contact 4.

50 The rod 3 is secured in a supporting base formed of two discs 5 and 6 of sheet insulating material, such as insulating fiber board. The lower disc 6 is provided with a circular slot 7 that extends substantially concentric with the periphery of the disc, the

ends of the slot terminating at a small angular distance from each other. The slot 7 is so formed that the upper edges 8 are located more remote from each other than the lower edges 9, whereby the surfaces between the edges 8 and 9 are inclined to the top and bottom surfaces of the disc 6, the edges 9 being formed by surfaces that form a lesser angle than the angle formed by the surfaces that join along the edges 8. A collar 10 of insulating material and which is substantially cylindrical in form is located in the slot 7, its ends terminating near or at the ends of the slot 7. The insulating collar or substantially cylindrical member 10 is provided with a resistance wire 11 that is wound on its surface, the windings being located in sufficient proximity to each other to permit a continuous contact between the wire and the spring contact 4 when the handle 1 is rotated and so that the spring contact 4 will readily slide over the windings of the wire.

55 The collar or cylindrical insulating member 10, together with the wire wound thereon, is forced into the slot 7. The bevelled sides of the slot 7, and particularly the corners formed by the edges 9, quite tightly clamped against the windings of the wire and thus operate to hold the wire and the cylindrical member 10 in position in the slot 7. The disc 5 is located above the disc 6 and thus the slot 7 forms a channel in the base in which the resistance wire and its insulating core 10 are secured. The two discs are secured together by means of the ring 12 60 of sheet material which is provided with a flange 13 extending substantially at right angles to the outer surface of the ring 12. The ring 12 is inserted over the edges of the discs 5 and 6 and then the edge portion 14 of the ring 12 is spun down over the edge of the disc 6, which clamps the narrow peripheral portion 15 of the disc 6 against the 65 resistance wire located on the core 10. This crowds the edges 9 against the wire throughout the length of the slot 7 and thus the resistance element of the rheostat is firmly clamped in position. It may also be held in position by means of lugs 16 formed on the ends of the substantially cylindrical collar 10. The lugs 16 fit under sleeves 17 located on the screws 18 that extend downward through the upper disc 5. Clamping 70 screws 18 may also be threaded into the lower ends of the sleeves 17 and form a

means for connecting an external circuit with the rheostat. They thus form binding posts of the rheostat. One of the sleeves 17 is connected with the shaft or rod 3 and 5 electrically connected with the contact 4, while one end of the resistance wire 11 is connected with the other sleeve 17 or the binding post that is formed by the sleeve 17 and the screws that are threaded therein. 10 By this arrangement the circuit passes from one binding post through the resistance wire to the contact 4 and thence to the other binding post, in the manner well known.

I claim:

- 15 1. In a rheostat, a resistance element arranged in substantially cylindrical form, a base formed of insulating material and having a slot located in proximity to the periphery and forming a flexible clamping portion in the peripheral portion of the base, and a ring for clamping and holding the edges of the channel against opposite sides of the resistance element.
- 20 2. In a rheostat, a resistance element arranged in substantially cylindrical form, a base formed of insulating material and having a slot located in proximity to the periphery and forming a flexible clamping portion in the peripheral portion of the base, and a ring located around the edge of the base and having an edge spun down against the flexible portion.
- 25 3. In a rheostat, a resistance element ar-

ranged in substantially cylindrical form, a base formed of a pair of discs, one of the discs having a slot in which an edge portion of the resistance element is secured by the clamping of the sides of the slot.

4. In a rheostat, a resistance element arranged in substantially cylindrical form, a base formed of a pair of discs, one of the discs having a slot in which an edge portion of the resistance element is located, and means for clamping and holding the edges of the slot against opposite sides of the resistance element.

5. In a rheostat, a resistance element arranged in substantially cylindrical form, a base formed of a pair of discs, one of the discs having a slot located in proximity to the periphery forming a flexible clamping portion, and means for clamping and holding the edges of the slot against opposite sides of the resistance element.

6. In a rheostat, a resistance element arranged in substantially cylindrical form, a base formed of a pair of discs, one of the discs having a slot located in proximity to the periphery forming a flexible clamping portion, and a ring for clamping and holding the edges of the slot against opposite sides of the resistance element.

In testimony whereof, I have hereunto signed my name to this specification.

LEONARD A. SEISS.
